UNITED STATES PATENT OFFICE.

WILLIAM A. BARTLEY, OF NEW YORK, N. Y.

CONTROL OF APPARATUS GOVERNING THE PASSAGE OF CARS ALONG RAILWAYS.

No. 802,676.

Specification of Letters Patent.

Patented Oct. 24, 1905.

Application filed February 24, 1905. Serial No. 247,094.

To all whom it may concern:

Be it known that I, WILLIAM A. BARTLEY, a citizen of the United States, residing in the borough of Manhattan, city, county, and State of New York, have invented certain new and useful Improvements in the Control of Apparatus Governing the Passage of Cars Along a Railway, of which the following is a specification.

- 10 The invention described herein relates to certain improvements in the control of automatically-operating train-stops, and more particularly to such automatically-acting train-stops as are used in conjunction with the brake or power systems of cars on steam or electric railways, and has for its object such arrangements of electrical circuits as will insure the operation of the train-stops controlled by such circuits at certain times.
- 15 20 The automatic train-stop to the control of which my invention relates consists, generally speaking, of a device, usually termed a "trip," actuated by electric or fluid pressure or any other suitable power and placed along-side of the railway, the said trip being adapted to engage, under certain conditions herein-after described, with an arm or lever depending from a passing car and by such engagement to apply the brakes or otherwise stop the passing car. The trip may occupy either one of two positions which we may call, respectively, the "operative" position and the "inoperative" position. When the trip is in the operative position, it will engage with the aforementioned arm of a passing car, and thereby stop the car; but when it is in the inoperative position it is entirely clear of any part of the passing car and will not stop it. On railways where automatic train-stops are used it is customary to equip all the cars of a train with depending arms or levers adapted to engage with a trip when said trip is in the operative position and the train is passing it, and consequently a train of several cars may be stopped by the arm on any car engaging with the trip, such engagement acting to apply the brakes of the passing car or cars or to shut off the motive power therefrom or to perform both operations. Ordinarily these stops are used in conjunction with a block-signal system and are placed adjacent to their respective signals and are so controlled that their trips move into the operative position at the same time that their respective signals assume the danger position.
- 25 It is an object of my invention to so con-

trol the movement of a trip that it will not move into the operative position until the whole train has passed it, although the signal with which it works in conjunction may have moved to the danger position as soon as the first car of the train has entered the section of track governed by said signal.

It is a further object of my invention to insure the trip assuming the operative position as soon as the entire train has passed it and, further, that the trip shall again assume its inoperative position as soon as the signal with which it works in conjunction returns to the clear position for a second train to enter the section. These objects I accomplish by the use of my circuits irrespective of the length of the train.

In order to describe the various arrangements of circuits embodied in my invention and their mode of operation, I have shown five diagammatic views—Figures 1, 2, 3, 4, and 5.

In Figs. 1, 2, 3, and 4, which show my circuits as applied to steam or electric railways, parts having like functions are designated by like reference characters.

Fig. 5 shows my system as applied to electric railways in which one or both track-rails are used as a return for the propulsion-current.

T designates a portion of railway-track which is divided into sections AB BC CD, &c., which are known as "block-sections." Each of these sections is separated from its adjacent sections by means of insulation 2^a 2^b, &c. Both track-rails may be so divided, as in Figs. 1, 2, 3, and 4, or only one of the track-rails may be divided, as in Fig. 5. In Fig. 5 provision may be made for using one or both of the track-rails for the return of the propulsion-current used for the motor-cars traveling along the railway. There may be any number of the above-mentioned block-sections and they may be of any length.

At the entrance end of each block-section is located a railway-signal of any suitable type and designated 1 1^a 1^b 1^c, &c. The operation of the signals in the present case is automatic and is controlled by the passage of a train along the railway. This control is effected in a manner well known to the art by means of track-circuits. Each block-section is provided with a track-circuit which, as is well known, comprises a battery or other suitable source of current-supply connected to the rails at one end of the block-section and a relay device

connected to the rails at the other end of the block-section, the said relay being supplied with current from the said source through the track-rails of the block-section.

5 In Figs. 1, 2, 3, and 4 the source of current-supply is in the form of a battery supplying direct current and the relay is of a type adapted to respond in the movement of its armature to the presence or absence of such current in its coils, the coils being connected to the rails and deriving their current, as above stated, from the said battery.

In Fig. 5 the relay receives its current from the same source of current-supply as is used for the propulsion of the cars and is of a form which will respond in the movement of its armature to the flow of said current through its coils.

Each relay controls a local circuit for the signal, and this local circuit controls the supply of motive power for the operating mechanism of the said signal. These local circuits, which are designated by the same characters in Figs. 1 and 2, may be traced therein as follows: Beginning at local battery 8 the current flows through contact-spring 5 of relay, wire 7, signal 1, and common return-wire 9 back to battery.

Any desired arrangement of circuits may be employed for controlling the operation of the railway-signals in any desired order. In Figs. 1 and 2 the simplest possible arrangement of track-circuit and local circuit is shown. In Figs. 3 and 4 two different systems of overlap-block sections are shown, involving the use of somewhat more complicated but fundamentally similar arrangements of signal-controlling circuits. There is a great variety of signal-controlling circuits used in connection with overlap-blocks, and I do not limit myself to the use of any specific type of such circuits, as they do not form a part of my invention. In Fig. 5 the signal-controlling circuit and the track-circuit are not shown, the relay of Fig. 5 being used exclusively for the control of my circuits.

10 10^a 10^b 10^c, &c., designate train-stops which are controlled by the circuits embodied in my invention. One of these train-stops is located at the entrance end of each block-section, though, if desired, they may be located at any convenient points adjacent the railway. Each stop comprises a trip 11 11^a, &c., which in its operative position engages 55 with an arm (not shown) carried by a car and controlling the brake or power system, or both, of the car and a suitable form of motor for moving the trip from its operative position and maintaining it in its inoperative position against the action of gravity or a spring which is employed to move it from its inoperative position to its operative position.

If desired, the motor may be employed to move the trip positively to its operative position as well as to its inoperative position.

I do not limit myself to the use of any specific type of train-stop so long as it is susceptible of electrical control. Each stop is, furthermore, adapted to operate a circuit-controller 13. When the trip is brought into 70 the inoperative position, the circuit-controller is operated to close a circuit, (the retaining-circuit).

When the trip is moved to its operative position, the circuit-controller is operated to open 75 this circuit. The use of this contact 13, which forms an important feature of my invention, I will presently describe. For convenience in illustration the said circuit-controller is shown as a finger operated directly from a 80 moving part of the stop mechanism; but the said device need not necessarily take that form.

Each trip in my invention is controlled as to its inoperative position by two circuits, 85 and when both or either of these two circuits are closed the trip will thereby be held in the inoperative position; but if both of these said circuits should be open at the same time the trip will move by gravity or other applied 90 force into the operative position. These two circuits I call, respectively, the "main" circuit and the "retaining-circuit." The main circuit is purely local to the stop which it controls and comprises the local battery or other 95 equivalent source of electrical energy, a contact made by the track-relay in Fig. 1, or a circuit-controller actuated from movement of the signal or signal mechanism, as in Figs. 2, 3, 4, and 5, the electromagnetic or other controlling device of the trip and wires connecting the above elements in any suitable order to one another. The retaining-circuit of any trip (in Figs. 1, 2, 3, and 4) starts from the local battery or equivalent source at a preceding signal, thence through a relay-contact at the said preceding signal, as in Fig. 1, or through a circuit-controller operated from said preceding signal, as in Figs. 2, 3, and 4, 100 thence by a line-wire to the said stop, where it goes through the contact 13 13^a, &c., hereinbefore referred to, which is closed, as above stated, by the movement of the said trip to the inoperative position, thence through the controlling device of the said trip, and thence 105 back again by a common return-wire to the other pole of the battery from which it started at the preceding signal. This method of control through a retaining-circuit originating from a preceding-signal station constitutes an 110 essential part of my invention, as shown in Figs. 1, 2, 3, and 4. The retaining-circuit which I show in Fig. 5 differs, however, from that shown in Figs. 1, 2, 3, and 4 in that it derives its energy from a source located at or near the trip controlled by said retaining-circuit and not from a source located 115 at the preceding signal.

Having now described broadly the relative positions and functions of the various elements 120

cooperating in my invention, I will more particularly describe the exact operation of my circuits and the trips they control.

Referring to Fig. 1, I have here shown a portion of railway-track T divided into three complete block-sections AB, BC, and CD, with the insulation 2, 2^a, &c., separating each section from the two adjoining ones. The direction of traffic on the railway T is from A to D. There may of course be other block-sections preceding A and succeeding D which are not shown. The entrance of trains to section AB is governed by a signal 1, which is shown in the clear position, thereby indicating that the section AB is clear of trains and that a train approaching signal 1 may enter the block. In like manner signal 1^a governs the block BC, and this signal is shown in the danger position, indicating that the block BC is occupied by a car or train of cars. This train is shown at E, and it will be seen that part of said train occupies the block CD, thereby holding the signal 1^b in the danger position. The signal 1^b governs the block DE, part only of which block is shown, and this signal 1^b is in the clear position. The train E having completely passed out of section AB, the track-relay 4 is energized by current which flows from its track-battery 3 through the rails of the block AB and the coils of the said relay 4. Consequently the armature of said relay will be attracted by the magnet-core of said relay, and the two contact springs or fingers 5 and 25, which are carried by the said armature, will respectively make contact with the wires 7 and 17, thereby completing the local circuit of the signal 1 and the main circuit of the stop 10. It will be seen that the said contact-springs 5 and 25 are both electrically connected to one pole of the battery 8, and under certain conditions, now to be described, current will flow from the battery through these contact-springs. Taking first the signal-circuit, we see that current will now flow from one pole of the battery 8, through relay contact-spring 5, wire 7, signal-operating mechanism, and wire 9 back to the other pole of battery 8, thereby moving the signal 1 to the clear position and maintaining it in that position so long as the relay 4 continues to be energized, and the contact-spring 5 is thereby held in the position shown. The main stop-circuit, which is likewise held closed by reason of the energized condition of the track-relay, may be traced as follows: Starting from one pole of the battery 8 current flows through contact-spring 25, wire 17, wire 15, controlling device of stop 10, wire 14, and wire 9 back to the other pole of battery 8. The completion of this circuit will have the effect of energizing the stop 10 and will thereby hold the trip 11 in the inoperative position. It will be seen, therefore, that in the system I am now describing the trip 11 is held in the inoperative position so long as the block-section

AB is clear of trains and the signal-relay 4 is thereby energized.

Referring now to block-section BC, it will be seen that a part of the train E is on this section, and the current from the track-battery 3^a has therefore two paths through which to flow, one being through the relay 4^a and the other through the wheels and axles of the car or cars that are on the said section BC. Under these conditions the current chooses 75 the path through the wheels and axles aforesaid, that being the path of least resistance, and the relay 4^a being thus deprived of energy drops its armature, thereby breaking the contact between 5^a and 7^a and that between 25^a and 17^a, at the same time making the contact at g' between 25^a and 18^a, and thereby completing the retaining-circuit of stop 10^b, to which circuit we will again refer. The contact between 5^a and 7^a being broken, the 85 signal-controlling circuit is opened, and the signal moves to "danger" in the usual manner. Furthermore, the contact between 25^a and 17^a being broken, the main circuit through the stop 10^a is likewise opened, and the stop 90 or its controlling device being thus deenergized the trip moves into the operative position, as shown.

Referring now to block-section CD, I there show its track-relay 4^b deenergized, owing to 95 the presence of part of the train E on the said block-section CD in the same manner that the track-relay 4^a of section BC is deenergized by a part of the same train E as already described. The relay 4^b being thus deenergized, 100 the contact between 5^b and 7^b is broken, and the controlling mechanism of signal 1^b being thereby deprived of electric energy the said signal 1^b moves to the danger position, as shown. Furthermore, the contact between 25^b 105 and 17^b is in like manner broken, and the main stop-circuit through 17^b is opened. Now if the stop were wholly dependent on its main circuit for energization it would now be deenergized, and the trip 11^b would move to the 110 operative position and apply the brakes or otherwise stop the passing train E in spite of the fact that the signal 1^b was in the clear position when the train began to enter the block CD. We have seen, however, that when relay 4^a at B was deenergized a contact was made at g' between the relay contact-spring 25^a and the wire 18^a, and this contact forms part of what I call the "retaining-circuit" of 115 the stop 10^b, which is located at C. This retaining-circuit may be traced as follows: Starting from one pole of local battery 8^a at B, the current flows through contact-spring 25^a, wire 18^a, circuit-controller 13^b, wire 16^b, wire 15^b, controlling device of stop 10^b, wire 14^b, wire 125 9^b, wire 19^b, common return-wire 20, and wire 19^a back to the other pole of battery 8^a. This retaining-circuit energizes stop 10^b with current derived from battery 8^a and holds the trip 11^b in the inoperative position, so that it 130

will not act to stop the train E. As soon, however, as the train E has completely passed off section BC the relay 4^a will again be energized by the current from its track-battery 3^a, and the contact between 25^a and 18^a will be broken, thereby opening the above-described retaining-circuit and depriving the stop 10^b of current from the source 8^a. I have already shown that the main controlling-circuit of stop 10^b is broken at the point f^3 between 25^b and 17^b. Consequently the stop 10^b is not deriving current either through its main circuit or its retaining-circuit, and the trip will consequently assume its operative position behind the train E and will maintain that position until the train E passes completely off section CD. As soon as the train has passed off the section CD the relay 4^b becomes energized once more and completes the main circuit of stop 10^b through the contact-point f^2 .

The condition of affairs at C after the train has passed off the block-section BC, but is still on section CD, is identical with that displayed in the diagram at B—that is to say, the relay at the entrance of the preceding block will be energized, as explained above, and the retaining-circuit through 10^b broken, thereby causing the trip 11^b to assume the operative position. As soon as the trip 11^b moves to the operative position the contact of the circuit-controller 13^b will be broken, and even if another train should now enter the block BC, and thereby cause the relay 4^a to make the contact between 25^a and 18^a, the retaining-circuit of stop 10^b will not be complete, because it has been broken at 13^b. The trip 11^b, having gone to the operative position behind the train E, which we are now supposing to have entirely passed into section CD, will remain in that position until the train has passed out of block CD, thereby allowing the armature of relay 4^b to complete the main circuit of stop 10^b by making a contact between 25^b and 17^b. As soon as this main circuit is again completed the trip 11^b will once more assume the inoperative position, thereby closing the contact of circuit-controller 13^b in readiness for a following train to enter block BC and by deenergizing relay 4^a complete the retaining-circuit of which 13^b forms a part, by closing the contact between 25^a and 18^a. From the foregoing description it will be seen that when any given block-section is clear of trains its governing-signal will be in the clear position and the trip which is placed in proximity to said signal will be in the inoperative position and the circuit-controller which is controlled by the movements of said trip will be closed. As soon as a train enters the block immediately preceding the said block the contact g or g' of relay belonging to said preceding block will be closed, and the retaining-circuit of the stop belonging to the block will be closed and will remain closed until the train 65 has entirely passed the said trip, and the said

trip will then assume the operative position and will remain in that position until the train has entirely passed off the block, and thus the train while traversing the block will have its rear protected from any following train so long as it remains in the block, and, furthermore, when the train has completely passed out of the block the stop which is located at the entrance to that block will again assume the inoperative position, and thereby allow a second train to enter the block.

In Fig. 2 I have shown an arrangement of circuits which is substantially the same as that of Fig. 1, except that in place of employing the contacts of track-relays to make and break the main and retaining circuits of the train-stops I use circuit-controllers f , f' , &c., and g , g' , &c., which are operated from some moving part of their respective signals or signal mechanisms. Thus the main stop-circuit of 10^c at D, for example, starts from battery 8^c and continues through wire 6^c, contact f^3 , which has been closed by the movement of signal 1^c to the clear position, thence through wire 17^c, wire 15^c, stop 10^c, wire 14^c, and wire 9^c back to the other pole of the battery 8^c, from which it started. The retaining-circuit of the same stop starts from battery 8^b at C and continues through wire 26^b, contact g^2 , which is closed by the movement of the signal 1^b to the danger position, thence through wire 18^b to contact 13^b at D, wire 16^b, wire 15^b, wire 14^b, wire 9^b, wire 19^b, common wire 20, and wire 19^b back to the other pole of the battery 8^b, from which it started.

In Figs. 1 and 2 like reference characters designate like parts of my apparatus, with the exception, as above stated, that in Fig. 2 circuit-controllers operated from the signals are used in place of the relay-contacts which I use in Fig. 1. The operation of the circuits is otherwise identical in the two cases.

Fig. 3 shows my circuits as applied to automatic stops working in conjunction with a block-signal system where overlap-sections are used, the overlaps in this case being of a length less than the distance between two adjacent signals. By the term "overlap" I mean that part of a block-section controlling a given signal which extends beyond the signal in advance of that one which the said block-section controls. For example, that part of the track which extends from the signal 1^a to the point α between signals 1^a and 1^b is the overlap of the block-section AB, and as far as the control of signal 1^a is concerned it forms a part of the section controlling said signal—that is to say, a train passing signal 1^a will move that signal to the danger position in the manner above explained in describing Fig. 1, and the signal having thus moved to the danger position will stay in that position until the train has passed the limits of the overlap-section. In other words, the signal 1^a will not move to the clear position until the

train has passed the point x . In like manner, when the signal 1^a has moved to the danger position it will stay in that position until the train has passed the point z . It is to be understood, of course, that when any part of a train is on an overlap-section it will cause both the signal immediately behind it and the signal to which the overlap belongs to assume the danger position. As regards the operation of my system it will be seen that part of the train E is standing on the section CD , thereby holding the signal 1^b in the danger position, and the circuit-controller f^2 , operated from said signal, is open. Consequently the main controlling-circuit of stop 10^b is open at f^2 . Now when the train passed the preceding signal 1^a it in like manner caused it to move to the danger position, thereby opening the circuit-controller f' and closing the circuit-controller g' . As soon as g' was thus closed current began to flow from battery 8^a at signal 1^a , through wire 26^a , contact g' , wire 18^a , circuit-controller 13^b on stop 10^b , wire 16^b , wire 15^b , controlling mechanism of stop 10^b , wire 14^b , wire 9^b , wire 19^b , common return-wire 20 , and wire 19^a , to the other pole of battery 8^a , from which it started. This retaining-circuit will maintain the stop 10^b in an energized condition, thereby holding the trip 11^b in its inoperative position until the train passes out of the overlap-section C^z . When the train has passed out of said overlap-section-signal 1^a will again assume the clear position, thereby opening the contact g' , and thus breaking the retaining-circuit of stop 10^b , which will then cause its trip 11^b to assume its operative position, and the said trip will stay in that position until the train has passed out of the next succeeding overlap-section.

Referring now to signal 1^a , it will be seen that it stands in the danger position, owing to the presence of the train in its overlap-section, and that the contact f' is thereby held open. Consequently the stop 10^a does not derive any current from its main circuit, of which the contact f' forms a part. Furthermore, the retaining-circuit of 10^a is also open at the contact g , operated from signal 1 , which is in the clear position. The stop 10^a therefore does not derive any current from its retaining-circuit either, and is consequently deenergized, thereby allowing its trip 11^a to assume its operative position, and the said trip 11^a will remain in its operative position until the train E has completely passed out of the overlap-section C^z , thereby allowing signal 1^a to move to the clear position and by such movement to close the main circuit of stop 10^a through the contact f' .

In Fig. 4 I show my circuits as applied to another system of overlap-blocks. In this system each overlap is of a length equal to a block-section. Consequently each signal is controlled by two complete blocks. Thus sig-

nal 1 is controlled by a train so long as any part of it is between A and C , signal 1^a is controlled by a train anywhere between the points B and D , and so on. The main circuits controlling stops are similar to those already described. The retaining-circuits, however, are controlled not from the next preceding signal, as in Figs. 1, 2, and 3, but from the second preceding signal, thus allowing the stop to return to the operative position immediately behind a passing train instead of waiting until the train has passed out of the overlap-section of the last preceding signal, as in Fig. 3. The stop is held clear, however, while a train is passing it through the medium of the retaining-circuit in the same manner as that already described in connection with Figs. 1, 2, and 3.

In Fig. 5 I show a circuit adapted for use on electric railways, in which I use the propulsion-current for energizing the stop-relay. This system is substantially the same as that already described in Figs. 2, 3, and 4, except that the retaining-circuit derives its energy from a source of current-supply located near the stop it controls instead of from a point near the entrance of a preceding block. In Fig. 5 I have not shown a continuous length of railway-track divided into various distinct but adjacent blocks; but I have shown three separate views of the same block-section. In the first view, A, I have shown the train E approaching the "clear" signal 1 and the trip in the inoperative position. In the second view, B, the train is passing the stop, the main stop-circuit is broken, and the retaining-circuit is closed, thereby holding the trip in the inoperative position and clear of the passing train. In the third view, C, the train is shown as having entirely passed the stop, and the retaining-circuit is now open and the stop is in the operative position.

As hereinbefore stated, Fig. 5 shows how I apply the circuits embodied in my invention to an electric railway, and I have chosen for my illustration a railway where what is known as a "third" rail is used as means for conveying electric power for propelling the cars and where one track-rail is used as a return-conductor for the propulsion-current in the usual manner, while the other track-rail is divided by insulation 2 into block-sections for the automatic control of block-signals. As in the preceding figures, 1 designates a railway-signal controlling the entrance of cars to the block-section T , 2 being the insulation which separates the block T from the preceding block-section S . 3 designates the third rail, from which the cars traveling on the railway derive their electrical energy. E is a train of cars provided in the usual manner with contact-shoes 4 and 4^a , one or more pairs of which are carried by each car. 5 designates a relay adapted to be operated by cur-

rent of the same nature as that used for propelling the cars and having one pole electrically connected to the short rail 9 by the wire or conductor 6 and the other pole electrically connected to the return-rail 19. A resistance r may be inserted in the circuit of the coils of said relay to cut down the current in said circuit to the required value. The numerals 8, 10, 11, 12, and 13 have the same significance as in the preceding figures of this specification. 14, 15, 16, 17, 18, 19^a, and 20 are wires or conductors forming parts of the circuits now to be described. The aforementioned short rail 9 is located close to the track on the side remote from the third rail at such a distance from the track that the contact-shoes of a passing car or cars will make contact with it in the same manner that the contact-shoes on the other side of the car or cars make contact with the third or power rail. Furthermore, the rail 9 is of sufficient length to insure each successive shoe of a passing car making contact with it before the preceding shoe has passed off it. Thus there will always be at least one contact-shoe of a passing train which will make contact with the short rail 9, and consequently as long as any car is passing the short rail 9 there will always be current flowing from the third rail 3 through contact-shoe 4 to contact-shoe 4^a and thence through the relay back to the return-rail 19. Suppose, now, a train E to be approaching signal 1 and to be making contact, as shown at A, between the third rail 3 and the shoe 4 on one side and between the shoe 4^a and the rail 9 on the other side. The signal 1 being in the clear position, the contact f is closed and current is flowing from one pole of battery 8, through contact f , wire 17, wire 15, stop 10, wire 14, back to the other pole of battery 8. The stop 10 is thus energized and the trip 11 is held in its inoperative position. This may be called the "main" circuit of the stop 10. We have seen that contact is now established between the shoe 4^a and the rail 9. Consequently current flows from the third or power rail 3, through contact-shoe 4, shoe 4^a, rail 9, wire 6, relay 5, resistance r , wire 7, to return-rail 19, thereby energizing the relay 5 and closing the contact at g . Current now flows through the stop-retaining circuit, which may be traced as follows: from battery 8, through wire 20, armature of relay 5, contact g , wire 18, contact 13, wire 16, wire 15, stop 10, wire 14, back to battery 8. This retaining-circuit, as in the cases previously described, is sufficient to energize the stop 10 independently of the main circuit, and it will continue to so energize the stop so long as a contact-shoe of any car of the passing train is still making contact with the rail 9. At B, I show the same train when it has partly entered the block-section governed by signal 1, the said signal having thereby been moved to the dan-

ger position in the usual manner. It will be seen that the main circuit is now broken at the contact f in the manner already described in reference to Figs. 2, 3, and 4, and the stop is now held in the inoperative position by the retaining-circuit. At C, I show the train as having passed entirely into the block T, thus breaking the continuity of the electrical circuit from rail 3 to rail 9, and thereby deenergizing the relay 5. The relay 5 being thus deenergized allows its armature to drop, thus breaking the retaining-circuit at the contact-point g , and thereby deenergizing the stop 10 and allowing the trip 11 to assume the operative position. The contact 13 is opened by the movement of the trip 11 to the operative position, and thus the retaining-circuit is prevented from being reestablished by the presence of a second train until the first train has passed out of the block T, thereby allowing the signal 1 to reassume the clear position and by closing the contact f to reestablish the main circuit. When the main circuit has thus restored the trip to its inoperative position, the contact 13 will thereby be closed again in readiness for the next succeeding train to establish the retaining-circuit.

What I claim as my invention is—

1. The combination with a series of block-sections of a railway, of an automatically-operating train-stop comprising a trip for each block-section, and two circuits for each train-stop either of which when closed prevents the trip from being moved to its operative position, one of said circuits being opened by the passage of a train into the block-section for which the stop is provided and the other of which circuits is closed through the action of the train in a preceding block-section.

2. The combination with a series of block-sections of a railway, of an automatically-operating stop comprising a trip for each block-section, two circuits for each train-stop, either of which when closed prevents the trip being moved to its operative position, one of said circuits being opened by the passage of a train into the block-section for which the stop is provided and the other of which is closed through the action of the train in the preceding block-section, and a circuit-controller in the circuit closed through the action of the train in a preceding block-section, which when actuated by a moving part of the stop when the trip moves to its operative position opens the said circuit in which it is included.

3. The combination with a series of block-sections of a railway, of an automatically-operating train-stop comprising a trip for each block-section, and two circuits for each train-stop either of which when closed prevents the trip from being moved to its operative position, one of said circuits being opened by the passage of a train into the block-section for which the stop is provided and the other of

which circuits is closed through the action of the train in a preceding block-section, and opened by the operation of the stop in the movement of the trip to its operative position.

4. The combination with an automatically-operating train-stop, comprising a trip and located at a point along a railway, of two circuits either of which when closed prevents the trip from being moved to its operative position, one of said circuits being closed before the train reaches the point at which the stop is located, the other of which is opened when a train passes the point of location of the stop and the first of which is also opened after the train passes the point of location of the stop.
5. The combination with an automatically-operating train-stop, comprising a trip and located at a point along a railway, of two circuits either of which when closed prevents the trip from being moved to its operative position, one of said circuits being closed before the train reaches the point at which the stop is located, the other of which is opened when a train passes the point of location of the stop, by the operation of the stop in the movement of the trip to its operative position.
6. The combination with two block-sections of a railway, each of which is provided with a track-circuit, of an automatically-operating train-stop located at the entrance end of the second block-section, and two circuits for said train-stop either of which when closed prevents the operation of the train-stop to move the trip to its operative position, one of said circuits being closed by the action of a train in its passage through the preceding block-section and opened by the passage of the train out of the preceding block-section.
7. The combination with two block-sections of a railway, each of which is provided with a track-circuit, of an automatically-operating train-stop located at the entrance end of the second block-section, and two circuits for said train-stop either of which when closed prevents the operation of the train-stop to move the trip to its operative position, one of said circuits being closed by the action of a train in its passage through the preceding block-section and opened by the passage of the train out of the preceding block-section.
8. The combination with an automatically-operating train-stop comprising a trip and located at a point along an electric railway, of a third or power rail conveying electric energy for the propulsion of cars upon the railway, a section of rail adjacent the railway, conductors carried by the cars and means of conveying current through said conductors from the third rail to the section of rail, a relay device adapted to be energized by said current, two circuits either of which when closed prevents the trip from being moved to its operative position, one of said circuits being closed through the energization of said relay device before the train reaches the point at which the stop is located, the other of which is opened when a train passes the point of location of the stop and the first of which is also opened after the train passes the point of location of the stop.

operation of the stop to move the trip to its operative position.

9. The combination with two block-sections of a railway, each of which is provided with a track-circuit, of an automatically-operating train-stop located at the entrance end of the second block-section, and two circuits for said train-stop either of which when closed prevents the operation of the train-stop to move the trip to its operative position, one of said circuits being closed by the action of a train in its passage through the preceding block-section and opened by the passage of the train out of the preceding block-section.

10. The combination with an automatically-operating train-stop comprising a trip and located at a point along an electric railway, of a third or power rail conveying electric energy for the propulsion of cars upon the railway, a section of rail adjacent the railway, conductors carried by the cars and means of conveying current through said conductors from the third rail to the section of rail, a relay device adapted to be energized by said current, two circuits either of which when closed prevents the trip from being moved to its operative position, one of said circuits being closed through the energization of said relay device before the train reaches the point at which the stop is located, the other of which is opened when a train passes the point of location of the stop and the first of which is also opened after the train passes the point of location of the stop.

In testimony whereof I have signed my name to this specification in the presence of two subscribing witnesses.
